CLAIM

The ornamental design for a tote bag for rolling walkers, as shown and described.

DESCRIPTION

FIG. 1 is a right side perspective view of a tote bag for rolling walkers;

FIG. 2 is a front perspective view thereof;

FIG. 3 is a front elevational view thereof;

FIG. 4 is a rear view thereof;

FIG. 5 is a left side elevation view thereof;

FIG. 6 is a right side elevational view thereof;

FIG. 7 is a top view thereof; and,

FIG. 8 is a bottom view thereof.

The broken lines in the drawings represent unclaimed environmental subject matter and form no part of the claim.
